Richard B. O'Brien,
ATTORNEY

UNITED STATES PATENT OFFICE.

WILLIAM POST, OF BROOKLYN, NEW YORK.

BANJO-BRIDGE.

1,383,752.

Specification of Letters Patent. Patented July 5, 1921.

Application filed November 1, 1919. Serial No. 335,130.

To all whom it may concern:

Be it known that I, WILLIAM Post, a citizen of the United States, residing at Brooklyn, in the county of Kings and State 5 of New York, have invented certain new and useful Improvements in Banjo-Bridges, of which the following is a specification.

This invention has relation to bridges for musical instruments, with particular reference to banjo bridges, and has for an object to provide a bridge constructed in a manner and of a material to act in such a manner when used on an instrument as to impart greater resonance, reverberation and volume 15 to the tone thereof.

In addition to the foregoing, this invention comprehends improvements in the details of construction and arrangement of parts, to be hereinafter described and particularly set forth in the appended claim.

In the accompanying drawings in which similar and corresponding parts are designated by the same characters of reference throughout the several views in which they 25 appear.

Figure 1 is a view in front elevation of a banjo bridge constructed in accordance with my invention.

Fig. 2 is a view thereof in longitudinal 30 section.

Fig. 3 is a view of the bridge in plan, and Fig. 4 is a transverse section.

With reference to the drawings it will be seen that the bridge consists of a transverse bar 10 which is substantially triangular in cross section and has its sides curved transversely. Formed upon the ends of the bar 10 are supporting legs 11 extending at right angles thereto. The legs are thicker at the 35 base than at the point of connection with the bar 10 and the sides are curved, forming a continuation of the curved sides of the bar 10 as would be observed from Fig. 4. It will be noted from Fig. 3 that the upper edge 40 of the bar 10 is flat and is widest at the intermediate portion of the bar 10 and narrowest at the ends thereof. The top surface of the bar 10 is formed with a plurality of notches 12 in which the strings of the instrument are held. The bar 10 is also provided 45 with a number of transversely extending openings 13, one centrally and two equidistantly therefrom at opposite sides of the center. The openings should be of the maximum size without unduly weakening the bar 50 for the purpose of supporting the strings.

The legs 11 are also bored from beneath by openings extending longitudinally of the leg and at right angles to the length of the bar 10 and to a distance short of the points of connection of said legs with the bar 10. An essential feature of the present invention consists in the material of which the bridge is constructed and for this purpose is used maple wood taken only from middle aged 55 trees and only from those trees which grow on high and dry ground.

Thus it will be seen that I have provided a banjo bridge which, by reason of its construction provides lightness and interferes as 60 little as possible with proper vibration of the sounding board of the instrument. It will also be observed that I have discovered a method of selecting wood from which banjo bridges may be constructed so as to provide 65 the greatest amount of resonance, reverberation and volume of tone.

While I have illustrated and described my invention with some degree of particularity I realize that in practice various alterations 70 therein may be made. I therefore reserve the right and privilege of changing the form of the details of construction or otherwise altering the arrangement of the correlated parts without departing from the spirit of 75 the invention or the scope of the appended claim.

Having thus described my invention, what I claim as new and desire to secure by 80 United States Letters Patent is:

A banjo bridge comprising a supporting bar which is triangular in cross section and having its apex slightly flattened to form a surface, said surface being widened at the intermediate portion of the bridge and with 85 both edges of said surface tapering to points at the ends of the supporting bar, said supporting bar being provided with transverse apertures, and supporting legs formed at the ends of the supporting bar extending at 90 right angles thereto, the sides of said legs being a continuation of the sides of the supporting bar, said supporting legs being bored 95 longitudinally thereof in their underside.

In testimony whereof I affix my signature 100 in presence of two witnesses.

WILLIAM POST. [L.S.]
